WILLIAM H. CLUNE, OF LOS ANGELES, CALIFORNIA.

ELECTRIC-WRITING SIGN.

1,054,336.

Specification of Letters Patent. Patented Feb. 25, 1913.

Application filed June 12, 1911. Serial No. 632,526.

To all whom it may concern:

Be it known that I, HARRY D. BROWN, a citizen of the United States, residing at Los Angeles, in the county of Los Angeles and 5 State of California, have invented new and useful Improvements in Electric-Writing Signs, of which the following is a specification.

This invention relates to an electric writing sign (or a sign on which any desired matter may be spelled out) of the class employing an aggregation of elements known as monograms and employing a certain operating mechanism for displaying or visualizing any desired characters on the monograms; and this invention has particularly 15 to do with the controlling mechanisms and the means of operating them rather than with the particular form of the monograms.

20 In arrangements and constructions heretofore there have been in common use monograms of different designs and arrangements. The monogram is merely an aggregation or group of lights in certain relative positions so that the lighting of suitable lights will show any desired letter or character. The controlling mechanisms for these lights constitute the bulk of the mechanism of such a writing sign. Fundamentally the controlling mechanism is such an 25 arrangement of switches and circuits as will enable the passage of current through any desired lights in any desired monogram; and on these fundamentals my system of 30 control is built up.

The normal features of my system are comprised mainly in my arrangement of circuits for the lighting of the lights and for the control of current through those 35 circuits. I have entirely separated the lighting circuits from the control circuits (preferably using a low voltage current for all the control circuits, while the ordinary high voltage is used for the lights). In these 40 controlling circuits I have provided arrangements which are the prime features of my present invention; and these arrangements, including relays and their circuits, are such as to provide for the following possible operations. As in all other devices of 45 this character, I am enabled to supply current to any desired light or lights in any particular monogram. But, beyond this, I am enabled to effect other operations of control peculiar to my own arrangement.

After lighting any desired lights in any desired monogram or monograms I may extinguish the lights in any or all of the monograms, and I may substitute other characters for those originally shown in any 60 or all of the monograms; all without interference with the showings in other monograms which are not wished to be changed. I have also provided a means whereby the monograms which are in operation (where 65 current is being supplied to some of their lights) are indicated by a luminous or other indicator on the keyboard of the machine and directly in front of the operator. This, in particular, is a great advantage as, in a 70 large number of cases, the operator is at some distance from the sign itself and is unable to see the effect he is producing unless by some complicated arrangement of mirrors or the like. And one of the prime 75 advantages of my system resides in the small number of circuits and wires necessarily employed; for my system of relays and their individual circuits obviates duplication of wiring.

80 In a broad manner I may describe my wiring arrangements as consisting in three sets of circuits; first, the lighting circuits; second, the controlling circuits (through the medium of which the lighting circuits 85 are controlled to supply current to any desired lights in any desired monograms); and third, the holding circuits (through the medium of which the lights in any or all of the monograms may be held illuminated or 90 extinguished). The exact relations of these circuits will be best understood from the following; but it will here suffice to say that the connection of the lighting circuits to the lights is controlled by individual relays, and these relays are controlled in their 95 actions by the controlling circuits and the holding circuits.

In the accompanying drawings I have shown a typical embodiment of my invention, in which drawings—

Figure 1 is a diagrammatic view illustrating the general arrangement of circuits for a sign consisting of nine monograms. Fig. 2 is a diagram illustrating the arrangement of wiring, exterior to the keyboard, for five of the lights of each of, say, the first two monograms. Fig. 3 is a partial plan of the lower part of the keyboard, the cover being removed. Fig. 4 is a longitudinal section 110

of the same. Fig. 5 is a similar section of the upper portion of the keyboard. Fig. 6 is a diagram illustrating the connections within the keyboard. Fig. 7 is a diagram illustrating the complete connections for a single light in each of two monograms or groups of lights.

In the drawings the numerals 1, 2, 3, 4, 5, 6, 7, 8 and 9 represent the different monograms of which the sign is composed, each of these monograms being possibly of the arrangement shown in Fig. 7. Lights 10 are so placed within suitable troughs or reflectors that, by the supply of current to any set of lights, any desired character may be shown. A keyboard 11 is illustrated as a typical form of manual controlling means; there being many mechanical forms in which this means may be assembled. The keyboard as illustrated is provided with a set of lettered, or otherwise character-distinguished, keys 12 and with two sets of numbered keys 13 and 14. Keys 13 and 14 are numbered to correspond with the numbering or positioning of the monograms in the sign; so that once the numbering of the monograms in the sign is understood, the correct key can be used by the operator to connect or disconnect the circuits of that monogram. I have also shown release and gang keys 15 and 16 located adjacent keys 13 and 14 respectively. Leading from keyboard 11 is a set of control wires A which lead to the sign and are each connected into each of the monograms through branch wires a. Current passing through wires A and a is controlled by the action of keys 12. Wires a connect to relays within the monograms, which relays control the passage of current from lighting circuit B to the individual lights. Wires b lead from the lighting circuit to the individual monograms and through these wires current is supplied to the lights. A series of selective wires C lead from the lower part of the keyboard 11 and lead one to each monogram; and these wires are so connected to the relays within the monograms that they form the return sides of circuits for wires A. The arrangement of switches and relays is such (to be hereinafter described) that upon the pressing down of one of keys 13 and of one of keys 12 current will be sent through certain of wires A and through whatever monogram corresponds to the key 13 operated. This current flowing through these control wires will immediately cause the operation of the relays to close the lighting circuits to certain lights; and the internal arrangements are such that, if the "1" key and the "A" key be pressed, then the letter "A" will be luminously shown on monogram No. 1. The arrangement within keyboard 11 is such that, after one of keys 13 is pressed down, thus making connection to the desired monogram,

then the circuit to that monogram will be held closed until the release key 15 is pressed. Thus the operator does not necessarily hold one of keys 13 down while he operates the desired one of keys 12.

After having made connection with the desired monograms, if the operator wishes to efface all the written matter, he has only to press down on gang key 16; but if, during the course of his writing on the sign he wishes to efface the matter in one or more individual monograms, he will press downwardly on the corresponding keys 14. These keys control the holding circuits through wires D and these wires D run one to each of the monograms. The function of these circuits is to hold the lighting circuits in the monograms closed after they have once been closed by the operation of keys 12 and 13; and the function of keys 14 and 16 is to operate the circuits through wires D to cause the lighting circuits within the monograms to open. With this general description of the operation of my sign I will now proceed to a detail description of the particular circuits and the operation of the switches and relays contained therein.

As before stated, each of the monograms contains a certain fixed number of lights, or of any other member capable of visualization by an electric current. Within the structure of each monogram there is contained a relay mechanism 20 for each light in the monogram. This is diagrammatically illustrated in Fig. 2, where five lights and relay mechanisms are shown for each of two monograms. Each of the relay mechanisms consists of a movable armature 21 adapted to control two switches 22 and 23 by its movement. A pair of electro-magnets 24 and 25 are adapted to attract the armature to close each of switches 22 and 23. Switch 22 of each of the relay mechanisms controls the passage of current through its corresponding light 10, each of the lights being connected in series with switch 22 and both switch and light being connected between wires B by means of a sub-circuit B' within the monogram and wires 26, 27 and 28 leading from the sub-circuit through the switch and light. Thus, when the armature of any relay mechanism is attracted by the electro-magnets, the circuit through the corresponding light 10 is closed and that light is visualized.

The means for actuating the relay mechanisms to close the switches and supply current to the lights is comprised in selective circuits C, control circuits A and the switches and other mechanism acting in conjunction with these circuits. One of wires C leads to each monogram and within each monogram a wire 30 leads from wire C to one side of electro-magnet 25. From the other side of each electro-magnet wire a leads and con-

nects to an individual wire A of the controlling circuits, wires A leading back to the keyboard 11. Wires 35 and 36 lead into the keyboard from any suitable source of electrical energy; and the operation of the keyboard is such that wire 35 is adapted to be connected with any desired ones of wires A, while wire 36 may be connected with any one or more of wires C. When such connections are made, the current will flow from wire 35 through keyboard 11, through certain of wires A, certain of wires a, certain of electro-magnets 25 and certain of wires 30, a certain one or more of wires C, keyboard 11, back to wire 36. By this action it will be seen that armatures 21 of certain definite ones of the relay mechanisms are drawn to the right (in Fig. 2) and current is supplied to corresponding lamps 10. At the same time that switches 22 are closed by the movements of the relay armatures, switches 23 are also closed. Switches 23 are connected in series with corresponding magnets 24 and both in series are connected with holding circuit wires D and D' through wires 40 and 41. Wire D' forms one side of the holding circuits for all of wires D, there being only a single wire D' and as many wires D as there are monograms. Wires D lead back to keyboard 11 and therein are normally connected to a wire 45 which leads from one side of a suitable source of electrical energy; while wire D' connects with a wire 46 which leads from the other side of that source. Wires D and wire 45 are normally all connected together so that, upon operation of any of the relay mechanisms by the means hereinbefore described, current will flow from wire 45 through keyboard 11, certain of wires D, certain of wires 41 connecting with those certain wires D, certain of magnets 24 and certain of wires 40 back to wire D' and wire 46. The arrangement within the keyboard is such that a pressure on any one of keys 14 will break the connection between wire 45 and corresponding wire D. Immediately the connection is broken the magnetism of magnets 24 ceases and the armatures heretofore attracted are allowed to move back to their original positions by means of a spring or gravity, as the case may be. The mechanical construction of these relays may be the same as shown and described hereinbelow. It is the idea of the arrangement that magnets 25 are only momentarily energized, so that, when the magnetism in magnets 24 ceases, the armatures are free to move to open the switches. When the switches open it is impossible to again energize magnets 25 until the switches in the keyboard are closed, or to energize magnets 24 until switches 23 are closed. The current to lights 10 is consequently cut off until another operation of approximate keys 12 and 13.

The foregoing described arrangement constitutes the basis of my invention; the structure and operation of the parts contained within keyboard 20 will now be explained.

The keyboard consists of a case 50 of any suitable design and arrangement, on which keys 12, 13, 14, 15 and 16 are mounted in any suitable manner so as to be pressed downwardly after the manner of typewriter keys. Each of keys 12 connects in some suitable manner with a movable switch bar 51. Switch bars 51 are of some longitudinal extent and carry spring pressed contact pins 53 set in them at suitable intervals and arranged over contact bars 52 which are set transversely of switch bars 51 and beneath them. There are as many bars 52 as there are lights in each of the monograms, and wires A connect with these bars 52. Wire 35 connects with switch bars 51 in any suitable manner as through a bar 35^a and the spring supports 51^a of the bars 51, so that, when any one of keys 12 is depressed and switch bar 51 is moved downwardly to engage certain of contact pins 53 with certain of contact bars 52, then current will flow from wire 35 through bar 35^a, supports 51^a, the bars 51 and pins 53 to certain of bars 52 and wires A. What wires A will thus be supplied with current depends upon the arrangement and number of pins 53 placed in bars 51; and the arrangement is made so that a pressure on any one of keys 12 will supply current to suitable wires A which will actuate corresponding relay mechanisms 20 to supply current to lights 10 which, when visualized, will present the character designated on the key 12.

Within the keyboard and beneath and corresponding to each of keys 13 is a relay mechanism 60. These relay mechanisms are duplicates of mechanisms 20, except that in mechanism 60 I have shown a single electro-magnet with double windings 61 and 62. The armatures 63 of these relay mechanisms are adapted to close switches 64 and 65 when attracted by the actions of the magnets. Beneath each of keys 13 is arranged a normally open switch 70, a pin 71 projecting downwardly from the key, being adapted to engage with the switch to close it when key 12 is pressed downwardly. Beneath release key 15 is a normally closed switch 72 adapted to be opened by the pressure of a pin 73 when key 15 is pressed downwardly. The above described mechanism is contained within that part of the keyboard which is normally arranged closer to the operator. Keys 14 and 16 are mounted on that part of the keyboard normally farther from the operator and beneath each key 14 is mounted a normally closed switch 75 adapted to be opened through the medium of a pin 76 when key 14 is depressed. Key 16 merely rests

130

mechanically on the arms 23^a of keys 14, and pressure on key 16 will press all of keys 14 downwardly and open all of switches 75. For each of keys 14 a third relay mechanism 80 is provided, this mechanism having double magnet windings 81 and 82, a movable armature 83 and armature controlled switches 84 and 85. In the upper part of the keyboard provision is made for a series 10 of small transparent panes 90 arranged somewhat as illustrated and numbered so as to be identified with the various monograms. Beneath each of these transparencies a small indicator light 91 is placed and 15 this light is supplied with current, through the medium of relay 80, as long as there is current flowing through the corresponding holding wires D.

Normally open switch 70 is connected on 20 one side by a wire 100 to wire 45 and on the other side it is connected by wires 101 and 102 to one side of one of the windings of each of relays 60 and 80. Wires 103 and 104 connect the other sides of these relay windings to a wire 106 which leads back to wire 46. On closure of switch 70 armatures 63 and 83 are both attracted and the four 25 switches 64 and 65, 84 and 85 are closed. Immediately these switches are closed current flows through the other windings of the electro-magnets to hold the armatures in position. For this purpose switch 64 is connected in series with magnet winding 62 by a wire 110, and wires 111 and 112 connect 30 the winding and switch with wire 106 and one side of normally closed switch 72, respectively. The other side of switch 72 is connected by a wire 113 with wire 100 which leads from wire 45. Switch 84 is connected 35 in series with winding 81 by means of a wire 120, while a wire 121 connects the other side of winding 81 with one side of normally closed switch 75, and a wire 122 connects the other side of switch 84 with wire 46. The 40 other side of normally closed switch 75 is connected to wire 45, while the first mentioned side of the switch 75 is connected to individual wire D. When the relay switches 45 are closed current will flow from wire 45 through wires 100 and 113, switch 72, wire 112, switch 64, wire 110, winding 62, wire 111 and wire 106 back to wire 46. This will 50 energize the relay magnet and hold switches 64 and 65 closed until switch 72 is opened. 55 To one side of switch 65 individual wire C is connected and to the other side of this switch wire 36 is connected. Thus, until switch 72 is opened, the circuit will be closed between wire 36 through switch 65 to wire 60 C. At the same time current will flow from wire 45 through switch 75, wire 121, winding 81, wire 120, switch 84 and wire 122 back to wire 46. This will energize the relay 65 magnets and hold relay switches 84 and 85 closed until switch 75 is opened. Light 91

is connected on one side by wire 130 with wire 45 and is connected on the other side by wire 131 with one side of switch 85. A wire 132 connects the other side of switch 85 with wire 122; so that, as long as switch 85 is closed, current will flow from wire 45 through light 91 and switch 85 back to wire 46. This current will flow, and light 91 will be visualized, as long as switch 75 remains closed. When switch 75 is opened it not only breaks connection between wires 45 and D (thereby breaking the holding circuit hereinbefore described) but it breaks the circuit leading through winding 81 and allows the relay switches to open. The relay 70 switches will remain open until current is sent through winding 82 again, this being accomplished by the closure of switch 70.

I will now follow out a typical set of circuits and explain a typical operation of the various mechanisms. Suppose that it is desired to show the letter "I" on monogram No. 1. Key 13 bearing the numeral "1" is depressed. This immediately closes corresponding switch 70 and operates both relays 80 and 80; effecting a closure of circuit between wire 36 and wire C¹, and a closure of circuit through light 91 which is located beneath transparency 90 bearing the numeral "1". The lighting of this transparency indicates that connections are made to monogram No. 1 and that that monogram is in condition to receive currents for causing visualization of any desired lights. Key 12 bearing the designation "I" is then depressed, and this causes connection to be made between wire 35 and certain of wires A (say, those wires A which are particularly shown in Fig. 2). Current immediately flows from wire 35 through wires A 100 and through the relay mechanisms 20 to wire C¹ and thence to wire 36, as hereinbefore set forth in detail. Relays 20 are thereby actuated and their switches closed, when current is immediately allowed to flow 105 through the holding circuits controlled by keys 14. The passage of current through these holding circuits and through magnets 24 of the relays will hold the relays closed and supply current to the desired lights until switches 75 are opened. When it is desired to erase the showing made in monogram No. 1, key 14 bearing the numeral "1" is depressed (or, if there are showings on other monograms wished to be effaced, key 120 110 may be depressed and the showings on all the monograms extinguished). The opening of switch 75 will cause the release of relay 80 and of relays 20 in monogram "1", causing the extinguishment of the 115 monogram showing and of light 91. Thus light 91 will indicate the monogram or monograms to which current is being supplied and as long as that current is supplied, the lights 91 being extinguished when the 120 125 130

monograms are extinguished. In this manner the operator is perfectly aware of the monograms in use and those not in use, being enabled to arrange his work upon the sign in a pleasing manner and also being enabled to have a check on what he has produced on the sign and what is yet to be produced. Relay 60 is released by the opening of switch 72 as soon as the operator has 10 pressed the desired key 12 and has visualized monogram "1" as desired. The opening of switch 72 releases relay 60 and allows switches 64 and 65 to open. This immediately cuts off the current through wire C¹ and wires A and places the whole apparatus in condition for the depression of another key 13 to connect with another monogram and the depression of any key 12 to visualize any desired character upon that monogram. 15 The operator's work is thus seen to consist of first deciding just how he will arrange the written matter on the sign, then depressing the required key 13 corresponding with the first monogram to be used, then the key 20 12 corresponding to the character to be placed in that monogram, and then the key 15 to release connection with that particular monogram. This operation is repeated until the whole matter is spelled out on the 25 sign. If the operator mistakenly depresses any of keys 12 or 13 and connects to the wrong monogram or places the wrong character in that monogram, he may immediately efface what he has written in that 30 monogram by a depression of corresponding key 14; and, after he had completely written the subject matter in hand, he can efface the whole showing by a depression of key 16. 35

It will be understood that I have made 40 the above described showing in a typical manner and have not endeavored to include all of the combinations or variations which may be included in the monogram. For instance, I may substitute characters on keys 45 12 other than those shown, and I may greatly increase the number of monograms without at all interfering with the nature of operation of my device. And I do not limit myself to incandescent or other lamps for 50 use in the monograms; any device will suffice which is capable of visualization by an electric current. I have also shown the manner of wiring connections which now appear to me most simple; but there are and 55 may be other systems of connection which will accomplish the same result in substantially the same manner. These I intend to be within the scope of my invention.

Having described my invention, I claim:

60 1. An electric sign, comprising in combination a plurality of groups of electrical illuminants, a group selector switch for each group, a plurality of character selector switches, and a normally closed release switch for each group, switches each con-

trolling electric current to one illuminant, means controlled by the group selector switches and the character selector switches to close the said illuminant controlling switches, means controlled by corresponding 70 release switches to hold closed the illuminant controlling switches of each group, an indicator illuminant for each group of the first mentioned illuminants, means whereby current is supplied to any one of said indicator illuminants simultaneously with the operation of the corresponding group selector switch, and means whereby current is cut off from any one of said indicator illuminants simultaneously with the operation of the corresponding group release switch. 75

2. An electric sign, comprising in combination a plurality of groups of electrical illuminants, a group selector switch for each group, a plurality of character selector switches, and a normally closed release switch for each group, a relay mechanism for each illuminant of each group, each relay mechanism comprising a pair of electro-magnets, an armature operable thereby and a pair of switches adapted to be operated by the action of the armature, circuits each including one of the illuminants and one of its corresponding relay switches in series, circuits each including in series the other of said relay switches and one of said relay magnets and a release switch corresponding to the same group, connections between one side of each of the other relay magnets of a complete group and the corresponding group selector switch, connections each leading from one of the character selector switches to the other side of one of said last mentioned relay magnets of each group, a single indicator illuminant for each group of first mentioned illuminants, means whereby current is supplied to an indicator illuminant simultaneously with the closure of the corresponding group selector switch, and means controlled by the corresponding group release switch to continue current to the corresponding indicator illuminant. 90

3. An electric sign, comprising in combination a plurality of groups of electrical illuminants, a group selector switch for each group, a plurality of character selector switches, and a release switch for each illuminant of each group, each relay mechanism comprising a pair of electro-magnets, an armature operable thereby and a pair of switches adapted to be operated by the action of the armature, circuits each including one of the illuminants and one of its corresponding relay switches in series, circuits each including in series the other of said relay switches and one of said relay magnets and a release switch corresponding to the same group, connections between one side of each of the other relay magnets of a com- 100

110

115

120

125

130

plete group and the corresponding group selector switch, connections each leading from one of the character selector switches to the other side of one of said last mentioned relay magnets of each group; a relay mechanism for each of the group selector switches comprising an armature adapted by its movement to close said group selector switch, another switch adapted to be closed by the movement of said armature, and a pair of electro-magnets adapted to operate the armature, a normally open switch and a circuit including it and one of said electro-magnets in series, a normally closed switch and a circuit including it and the other electro-magnet and the other armature operated switch in series; an indicator mechanism for each group of first mentioned illuminants, comprising an indicator illuminant, a switch connected to the indicator illuminant, means for closing said switch when the corresponding one of said normally open switches is closed, and means controlled by the corresponding group release switch to hold said indicator switch closed.

4. An electric sign, comprising in combination a plurality of groups of electrical illuminants a group selector switch for each group, a plurality of character selector switches, and a normally closed release switch for each group, a relay mechanism for each illuminant of each group, each relay mechanism comprising a pair of electro-magnets, an armature operable thereby and a pair of switches adapted to be operated by the action of the armature, circuits each including one of the illuminants and one of its corresponding relay switches in series, circuits each including in series the other of said relay switches and one of said relay magnets and a release switch corresponding

to the same group, connections between one side of each of the other relay magnets of a complete group and the corresponding group selector switch, connections each leading from one of the character selector switches to the other side of one of said last mentioned relay magnets of each group; a relay mechanism for each of the group selector switches comprising an armature adapted by its movement to close said group selector switch, another switch adapted to be closed by the movement of said armature, and a pair of electro-magnets adapted to operate the armature, a normally open switch and a circuit including it and one of said electro-magnets in series, a normally closed switch and a circuit including it and the other electro-magnet and the other armature operated switch in series; an indicator mechanism for each group of first mentioned illuminants and comprising an indicator illuminant and a relay mechanism including an armature, a pair of switches adapted to be closed by the movement of the armature, and a pair of electro-magnets for operating the armature, a circuit including one of said switches one of said magnets and the corresponding group release switch in series, a circuit including the other of said switches and the indicator illuminant in series, and a circuit including in series the other of said magnets and the normally open switch of the relay mechanism for the corresponding group of illuminants.

In witness that I claim the foregoing I have hereunto subscribed my name this 23d day of May, 1911.

HARRY D. BROWN.
